UNITED STATES PATENT OFFICE.

ERASMUS HELM, OF TUXEDO PARK, NEW YORK.

CLASP FOR GARTERS, ETC.

1,424,301.

Specification of Letters Patent. Patented Aug. 1, 1922.

Application filed September 7, 1921. Serial No. 499,075.

To all whom it may concern:

Be it known that I, ERASMUS HELM, a citizen of the United States, residing at Tuxedo Park, in the county of Orange and State of New York, have invented new and useful Improvements in Clasps for Garters, Etc., of which the following is a specification.

This invention relates to garters.

10 The object of the invention is to provide a garter, embodying among other characteristics, means for applying the garter to the wearer's drawers and stocking to support the latter without wrapping or tying the 15 elastic material about the wearer's leg to the latter's discomfort and without interfering with blood circulation of the user of the garter.

With the above and other objects in view 20 the invention consists in the novel construction, combination and arrangement of parts hereinafter fully described, illustrated in the accompanying drawings and pointed out in the claims hereto appended, it being understood 25 that various changes in the form, proportion and minor details of construction, within the scope of the claims, may be resorted to without departing from the spirit or sacrificing any of the advantages of the 30 invention.

In the drawings in which like characters of reference designate corresponding parts in the several figures:

Figure 1 illustrates the complete invention. 35 Figure 2 is an enlarged front view of the upper clasp.

Figure 3 is an enlarged longitudinal sectional view of the upper clasp.

Figure 4 is an enlarged top plan view of 40 the same.

Referring now more particularly to the accompanying drawings, the reference character 5 indicates a piece of elastic material of a suitable character and length to the lower 45 end of which a stocking or sock engaging clasp 6 of any suitable character may be secured in any suitable manner, the clasp shown being one of the double clasp variety.

A clasp A is secured to the upper end of 50 the elastic material 5 in any suitable manner. This clasp is of peculiar formation and comprises two jaws.

The free edges of the parts 9 of the jaws a and b are preferably serrated to provide 55 teeth 12 with the teeth of the respective jaws

interengaging to take a firm hold on the wearer's drawers. To insure this firm connection of the jaws of the clasp A with the wearer's drawers, open ended sockets 13 are struck up from or formed on the inner face 60 of each part 8, to receive the ends of the springs 14 encircling the hinge pintle 11, as shown. This form of clasp provides a hollow interior which confines that part of the wearer's drawers pinched between the jaws 65 of the clasp.

By simply grasping the clasp A along the web portions 10 as shown in Figure 1 and forcing the jaws a and b to throw their parts 8 toward each other against the action of the 70 springs 14, the toothed edges of the parts 9 of the jaws are separated to receive the wearer's garment and by placing the separated toothed edges of the jaws against the wearer's drawers, and releasing the hold on 75 the jaws, the springs 14 will cause the toothed edges of the jaws to snap over the wearer's garment and hold against accidental disconnection.

From the foregoing it will be seen that the 80 upper clasp is composed of two substantially U-shaped sides abutting, providing a hollow body open at its ends only when the clasp is closed. It will also be seen that I provide a garment supporter designed to overcome 85 the inconvenience occasioned in the use of tight bands usually employed in the "make-up" of garters, sleeve supporters, etc. It will also be appreciated that my improved 90 clasp is positive in operation and it is to be understood that its use is not limited to garters, and sleeve holders, but that my improved clasp may be used wherever a clasp of the present character may be serviceable.

1. A garment supporter comprising a strip 95 of elastic material, a clasp secured to one end of the elastic material, and another clasp secured to the other end of the elastic material and consisting of a pair of substantially U-shaped members hingedly connected together to form a substantially hollow body, the jaws having inter-engaging teeth and springs mounted within the hollow body and having engagement with the hinging connection of the jaws to maintain the teeth of 100 105 the jaws normally in interengaging relation.

2. A garment supporter comprising a flexible element, a clasp secured to one end thereof and another clasp at the other end of the said flexible element, the second clasp 110

comprising a hollow body divided vertically into two sections having side walls and parallel front and rear walls, the said sections having hinged connection with each other and having interengaging teeth on the abutting edges of each section, the said clasp adapted to wholly confine the end of the

material gripped thereby within the hollow body, and a spring coating with the hinged connection to urge the sections into gripping position.

In testimony whereof I hereunto set my hand.

ERASmus HELM.
